UNITED STATES PATENT OFFICE

2,416,694

TRANSMISSION LINE VOLTAGE INDICATOR

David A. Howard, Jr., Hartwell, Ga.

Application January 2, 1945, Serial No. 571,059

4 Claims. (Cl. 171—95)

(Granted under the act of March 3, 1883, as
amended April 30, 1928; 370 O. G. 757)

1

The invention described herein may be manufactured and used by or for the Government for governmental purposes, without the payment to me of any royalty thereon.

The invention to be hereinafter described relates to indicators for tuning radio transmitters.

Heretofore, in such work, it has been common practice to use plate current milliammeters, thermocouple ammeters, light bulbs or wattmeters employing dummy loads. Various disadvantages and objections are inherent in those instruments. Plate current milliammeters are often misleading and they are difficult for inexperienced personnel to use. Thermocouple ammeters are slow acting. Light bulbs must be actually built into the transmitter. They consume more current than required by the present invention. Wattmeters, employing dummy loads, representing an antenna load, seldom possess the same impedance as that of the antenna for which the dummy load has been substituted. They, too, are slow acting.

The main objects of the present invention are to completely overcome or minimize the above and other objections and provide a simple, compact, quick acting efficient instrument, usable over a wide range of frequencies, readily transferable from one transmitter to another and capable of definitely revealing the presence and magnitude of standing waves.

In order to more clearly disclose the construction, operation and use of the invention, reference should be had to the accompanying drawings forming part of the present application.

Throughout the several figures of the drawings like reference characters designate the same parts in the different views.

In the drawings:

Fig. 1 is a side elevation of the invention;

Fig. 2 is a cross section through Fig. 1, enlarged, showing in diagram, the electrical features; and

Figs. 3 and 4 are diagrammatic illustrations of the use of the invention.

Briefly referring to the drawings in detail, especially Fig. 2, the instrument of the invention comprises a suitable case, box, or housing T in which are disposed, according to the diagram shown, or its approximate equivalent, the following elements: A carbon resistor R of suitable range such as 25,000 ohms; a crystal rectifier X of very high frequency or microwave type; a condenser C of, for instance, .001 m. f. d.; a short section of coaxial line L; connection S for line L; and a meter jack J with plug in connection for suitable connection to a meter M, such as

2

a microammeter, milliammeter or vacuum tube voltmeter, such meter, however, forming no part of this invention. There is, of course, an electric circuit conductively and capacitively including the above mentioned elements of the invention within the housing, as shown. The instrument of this invention, in operation in a transmission line with suitable connections S, produces a direct current which, in turn, is detectable by a meter M.

- 10 The invention, after being coupled or connected in the line will produce meter deflections in any of the above mentioned types of meters. Such deflection is a direct indication of the power output of the transmitter being tuned.
- 15 If the line is relatively free of standing waves the power output will be equal to E^2 divided by R where R is the characteristic impedance of the transmission line, E being the voltage existing between the inner and outer conductors of the line. E may be read directly by calibrating the equipment, although a relative reading is sufficient.

- 20 If standing waves are suspected on a transmission line the following procedure, with the use of this invention, will indicate their presence and magnitude. Two sections of line having the same characteristic impedance as the transmission line being investigated are connected in series with the transmitter and transmission line. Preferably, the sections should have $\frac{1}{4}$ wave and $\frac{1}{8}$ wave electrical length. Figs. 3 and 4, collectively, indicate points (1, 2, 3 and 4) at which the invention should be inserted, such connections being made in usual and well known manner.
- 25 The readings given at such connections will give the line voltage at the transmitter, $\frac{1}{8}$ wave from the transmitter, $\frac{1}{4}$ wave from the transmitter and $\frac{3}{8}$ wave from the transmitter. By plotting these voltages against wave length, the standing wave ratio can be determined, thus revealing the existence and magnitude of the suspected standing waves. Standard matching procedures may now be employed to eliminate the standing waves. When the standing waves have been eliminated 30 the meter will indicate equal values at all four points (1, 2, 3 and 4).

Adaptation of the device for open wire lines will be well understood by those skilled in the art to which the invention relates.

35 It is thought that the construction, operation and use of the invention will be clear from the preceding detailed description.

Changes may be made in the construction and disposition of the various parts of the invention within the scope of the appended claims with-

out departing from the field of the invention, and it is meant to include all such within this application wherein only one preferred form has been illustrated purely by way of example and with no thought or intent of, in any degree, limiting the invention thereby.

Having thus described my invention, what I claim and desire to protect by Letters Patent is:

1. An instrument for indicating the presence and magnitude of standing waves on a transmission line comprising a housing, a section of coaxial line mounted thereon and extending therethrough and provided with end connectors exterior to said housing whereby said instrument may be selectively inserted in a transmission line, a circuit in said housing and including said section of coaxial line, a resistor in said circuit, a crystal rectifier in series with said resistor in said circuit, a condenser in series with said resistor and said rectifier in said circuit, and a jack in said circuit for plug-in connection.

2. An instrument for indicating the presence and magnitude of standing waves on a transmission line comprising a housing, a section of coaxial line mounted therein and extending therethrough and provided with end connectors exterior to said housing whereby said instrument may be selectively inserted in a transmission line, a circuit in said housing and including said section of coaxial line, a carbon resistor in said circuit having a range of the order of 25,000 ohms, a crystal rectifier in series with said resistor in said circuit, a condenser in series with said resistor and said rectifier in said circuit, and a jack in said circuit for plug-in connection.

3. An instrument for indicating the presence and magnitude of standing waves on a transmission line comprising a housing, a section of coaxial line mounted therein and extending there-

5 through and provided with end connectors exterior to said housing whereby said instrument may be selectively inserted in a transmission line, a circuit in said housing and including said section of coaxial line, a resistor in said circuit, a microwave type crystal rectifier in series with said resistor in said circuit, a condenser in series with said resistor and said rectifier in said circuit and a jack in said circuit for plug-in connection.

10 4. An instrument for indicating the presence and magnitude of standing waves on a transmission line comprising a housing, a section of coaxial line mounted therein and extending therethrough and provided with end connectors exterior to said housing whereby said instrument may be selectively inserted in a transmission line, a circuit in said housing and including said section of coaxial line, a carbon resistor in said circuit having a range of the order of 25,000 ohms, a microwave type crystal rectifier in series with said rectifier in said circuit, a condenser in series with said resistor and rectifier in said circuit and a jack in said circuit for plug-in connection.
